UNITED STATES PATENT OFFICE.

FRANS H. C. COPPUS, OF WORCESTER, MASSACHUSETTS, ASSIGNOR TO COPPUS ENGINEERING AND EQUIPMENT COMPANY, OF WORCESTER, MASSACHUSETTS, A CORPORATION OF MASSACHUSETTS.

TURBINE-DRIVEN BLOWER.

1,244,427.

Specification of Letters Patent. Patented Oct. 23, 1917.

Original application filed November 11, 1912, Serial No. 730,561. Divided and this application filed April 19, 1915. Serial No. 22,479.

To all whom it may concern:

Be it known that I, FRANS H. C. COPPUS, a citizen of the United States, residing at Worcester, in the county of Worcester and Commonwealth of Massachusetts, have invented a new and useful Improvement in Turbine-Driven Blowers, of which the following, together with the accompanying drawings, is a specification.

10 The present invention relates to a turbine-driven blower; and the same contemplates an improved arrangement of the turbine and the blower constituting such a set, whereby the disposal of the exhaust steam 15 from the turbine is facilitated, the back pressure within the casing of the turbine is reduced, and the action of the blower is improved.

This application is a division of my co-pending application Serial No. 730,561, filed November 11, 1912, for a steam turbine.

The features of the present invention are fully set forth in the following description and pointed out in the annexed claims, reference being had to the accompanying drawing, in which the single figure is a sectional view of the apparatus embodying my invention.

In said figure, the numeral 1 denotes a 30 turbine wheel, having the usual buckets or blades 2. Rotary motion is imparted to said wheel by means of steam under pressure, admitted by a supply pipe 3 to the steam chamber 4, formed in the casing 5 which incloses said wheel. The shaft 6 of said turbine wheel, which is suitably journaled in the casing 5, carries on its outer end a fan 7, disposed within the mouth of a casing or conduit 8, through which said 40 fan serves to force a current of air, used for ventilating purposes, or to produce an artificial draft, in the ash pit of a boiler, or for any other purpose.

The exhaust opening 9 of the casing 5 opens laterally therefrom in the direction of the conduit 8; a pipe 10 is threaded therein, and the other end of said pipe has a snug sliding fit within a tubular passage 11 formed in the wall of the blower conduit

8, to permit of expansion and contraction of 50 the connected parts. The passage 11 communicates through a discharge passage 12 with the interior of the conduit 8, contiguous to the fan 7. Said discharge passage 12 is directed into the interior of said conduit 8 at an oblique angle to the axis of the fan 7, so that the movement of air through the conduit 8, by said fan, in the direction of the arrow *a*, induces a current 60 through the passage 11 in the direction of the arrow *b* thereby reducing the back pressure of the steam in the steam chamber 4, and causing the exhaust steam from the turbine to become thoroughly intermingled with the air set in motion by the blower. 65

I claim—

1. In a device of the class described, the combination with a turbine, of a blower driven thereby, and having an inclosing casing, and means for delivering the exhaust 70 steam from said turbine into the casing of said blower in a direction corresponding to the movement of air through said casing.

2. In a device of the class described, a shaft, a turbine wheel carried by one end of 75 said shaft, a fan blower carried by the other end of said shaft, a casing inclosing said turbine wheel having an exhaust opening, a second casing inclosing said fan blower having an exhaust passage, means for connecting said first and second casings with a space between them, and a pipe connecting said exhaust opening of the first casing with said exhaust passage of the second casing. 80

3. In a device of the class described, a 85 casing, a steam turbine inclosed therein, a second casing spaced from said first casing and having open ends, a fan blower inclosed therein, and a steam exhaust passage leading from said first casing and opening into 90 said second casing in front of said fan blower.

4. In a device of the class described, a 95 casing, a turbine wheel inclosed therein, a second casing spaced from said first casing and having open ends, a fan blower inclosed therein, a steam exhaust passage leading from said first casing and opening into said

second casing in front of said fan blower, with the delivery end of said exhaust passage at an oblique angle to the axis of said fan blower.

5. In a device of the class described, the combination with a steam turbine, of a blower driven thereby, a casing inclosing said blower, and means for delivering the

exhaust steam from said turbine into said casing.

10

Dated this thirteenth day of April 1915.

FRANS H. C. COPPUS.
